UNITED STATES PATENT OFFICE.

LUCIEN I. YEOMANS, OF WALWORTH, NEW YORK, ASSIGNOR TO GOODELL COMPANY, OF ANTRIM, NEW HAMPSHIRE.

FRUIT PARER AND CORING MACHINE.

SPECIFICATION forming part of Letters Patent No. 718,687, dated January 20, 1903.

Application filed May 16, 1902. Serial No. 107,576. (No model.)

To all whom it may concern:

Be it known that I, LUCIEN I. YEOMANS, a citizen of the United States, residing at Walworth, in the county of Wayne and State of 5 New York, have invented an Improvement in Fruit Parer and Coring Machines, of which the following description, in connection with the accompanying drawings, is a specification, like characters on the drawings representing 10 like parts.

This invention has for its object the production of a novel machine by which to rapidly pare and core fruit and remove the same from the coring-blade.

15 The machine is devised also to automatically discharge the core from the fork.

The particular features in which this invention consists will be fully described in the specification and pointed out in the claims 20 thereof.

Figure 1 in side elevation represents a machine embodying my present invention in one of the best forms now known to me. Fig. 1^a is a detail referring to the clamping-hub holding the coring-blade. Fig. 1^b is a detail showing the core detached from the machine, said core being also represented in Figs. 1 and 1^a. Fig. 2 is a plan view of the machine shown in Fig. 1. Fig. 3 is a sectional detail in the line 25 α , Fig. 2. Fig. 4 is also a partial sectional detail in the line α , Fig. 2. Fig. 5 is an under side view of the casting shown in Fig. 4 in section and the arm or lever to which the knife-carrier and knife are secured. Fig. 6 30 is a detail showing the stop-plate detached. Fig. 7 is a sectional detail of the core-discharging means. Fig. 8 is a section looking to the right of the dotted line α^a , Fig. 7. Fig. 9 is a section in the dotted line α^b , Fig. 7.

40 The framework A of the machine is of suitable shape to sustain the working parts, to be described. The right-hand end of the machine-frame has a base part A', (shown best in Fig. 1,) it being adapted to set on a table, 45 and the left-hand end A² of the machine is extended forwardly from the base, leaving an overhanging part with a space below it in which the coring-blade and the paring-knife may be moved, said coring-blade and paring-knife depending below the overhanging end 50 of the frame.

The framework has suitable lugs A³, that receive and sustain a guide-rod A⁴, that is embraced by hubs A⁵ of a carriage A⁶, having a foot A⁷, that rests upon and partially embraces a guide-rod A⁸, held in the base of the frame. This carriage sustains the turn-table, to be described, carrying the paring-knife and also the coring-blade, and said carriage and blade are moved to and fro during each paring and coring operation, the turn-table carrying the paring-knife being partially rotated during such action and the coring-blade being tipped that the cored fruit held upon the coring-blade may be discharged therefrom by 65 a suitable doffer, to be described.

The outer or right-hand end of the carriage A⁶ is bored to receive loosely a stud B, with which is connected by suitable set-screws an H-shaped frame B^X, represented as having 70 four bearing-points, that in the sliding movement of the carriage A⁶ contact with the lower edges of suitable guides, as C. The outer part A² of the framework sustains two such guides, only one being shown in Figs. 1 and 75 2, each guide being acted upon by two of the bearing-points of the frame B^X.

Each guide C is slotted at C², and bolts C', extended through said slots, enable the position of the guide to be changed to provide for 80 wear between it and the carriage B^X, and by extending the bolts C' through slots C³ in the part A² of the framework the guides may be adjusted longitudinally to provide for the turning of the frame B^X at any desired point 85 in its outward throw. The guide C has connected with it by bolts ca a depending doffer C⁶, that stands in a plane at one side the plane of movement of the coring-blade B².

The stud B has secured to it the part B' of 90 the coring-blade carrier, other parts of said carrier being designated as an arm B⁸, connected with the part B' by a suitable bolt B⁴, and a split carrying-sleeve B⁶, connected with said arm by a bolt B⁵. The split carrying- 95 sleeve has a set-screw a^X , (see Fig. 1^a,) that may be made to contract the split carrying-sleeve and clamp firmly the coring-blade bushing B⁷, said bushing being shaped to present a space, as shown in Fig. 1^b, having longitudinal shoulders 100. The rear end of the coring-blade is inserted in space 60. The concaved

inner side of the blade contacts with the convexed bottom 62 of the space, said bottom being in a circle of a lesser arc than the circle defining the rest of the body. The side edges 5 of the blade contact with the shoulders 61 of the space 60.

In fitting the bushing for use the exterior thereof is made to correspond as nearly as possible with the circle occupied by the exterior of the coring-blade, and one-half of the bushing at one side of a line longitudinal to the axis thereof is reduced and shaped to exactly fit the interior concaved side of the coring-blade, so that said blade whenever inserted in the clamping-hub and sustained by the bushing may be accurately held and positioned wherever desired.

The lever B' of the coring-blade has an upwardly-extended lug b, that as the carriage 20 A⁶ is moved to the left after the fruit has been pared meets the adjustable stud C⁵ just as the left-hand bearing-points of the frame B^X arrive at the rounded ends 20 of the guides C and cause the coring-blade to be tipped, 25 the stud B turning in the end of the carriage A⁶, and during this operation the cored fruit held on the coring-blade striking the edge of the doffer C⁶ and ejected from the coring-blade dropping into any suitable receptacle.

30 The carriage A⁶ has secured to it by suitable screws E an arch E', (see Fig. 2,) the upper end of which (see Fig. 4) receives a post E², the post being retained in the arch by a suitable nut, as E³. The post has a shoulder 35 a⁴, that sustains a turn-table E⁴, provided at its lower end with a series of teeth a⁵, (represented as three in number,) the lower end of the turn-table being slotted at E⁵ to receive the rod E⁶, having at its upper end a hook 40 (see Fig. 4) to engage a projection a⁶ of the turn-table and suspend the rod E⁶ loosely. The rod E⁶ has connected to its lower end in usual manner the knife-carrier a^{5X}, containing the usual knife employed for paring the 45 fruit. The lower end of one of the teeth a⁵ has inserted in it a screw b¹, said screw being made to sustain a plate b², provided with a series of notches, (represented in plan view in Fig. 6,) into any one of which the arm E⁶ may 50 enter whenever the fruit of whatever size is removed from the fork, a spring b³, connected with said lever and with said tooth, acting to seat the arm E⁶ in one of said notches when the fruit is off the fork, thus preventing the 55 paring-knife from contacting with the fork.

As has been stated, the carriage A⁶ is moved to and fro—i. e., it is moved to the right, viewing Fig. 1, when the fruit is to be pared and to the left after the completion of the paring 60 operation.

The part A² of the frame has a slotted bracket G, to which is secured by suitable screws G² a toothed plate G', that as the carriage A⁶ is moved to and fro engages the teeth 65 a⁵ of the turn-table and rotates the carriage, causing the knife-carrier and paring-knife to

travel about the circumference of the fruit from one to its other end.

Referring to Figs. 2 and 4, it will be seen that the post E² occupies a position directly 70 over the longitudinal axis of the fork-shaft H⁶, and consequently over the axis of rotation of the fruit, so that the cutting edge of the paring-blade is always presented at the same angle to the exterior surface of the apple, 75 whatever its size or shape.

The framework sustains a shaft D⁶, that carries a beveled toothed gear D⁵, having secured to it a partial gear D⁴, and at a distance from said shaft said gear D⁵ has secured to it 80 a segmental rack D⁷.

That the carriage may be moved as stated said carriage has connected with it by suitable bolts a² a rack D, that is engaged by a gear D', secured to a shaft D², mounted in 85 suitable bearings in the frame, said shaft having a pinion D³, that may be engaged either by a partial gear D⁴ or by the segmental series of teeth D⁷.

To rotate the gear D⁵, I have mounted upon 90 a stud at the end of the frame a toothed wheel H', having at its inner side a bevel-gear H², that engages the bevel-teeth of the gear D⁵. Nut H holds the gear on the stud and, as herein shown, the gear H' is illustrated as 95 being driven by hand, and for this purpose it is provided with a handle H³. The peripheral teeth of the gear H' engage an intermediate gear H⁴, that in turn engages a gear H⁵ on the fork-shaft H⁶, thus rotating said fork, 100 and with it the fruit which may be impaled thereon.

When the gear D⁵ is rotated in the direction of the arrow, Fig. 1, the partial gear D⁴, in engagement with the pinion D³, will turn the 105 shaft D² in a direction to cause the gear D', engaging the teeth D of the carriage A⁶, to draw the same to the right; but after the teeth of the partial gear D⁴ run out of mesh with the teeth of the pinion D³ then the segmental rack D⁷ engages the teeth of the pinion D³ and turns the shaft D² in the opposite direction, thus causing the gear D' to slide the carriage to the left at a speed faster than its forward movement. 115

The fork-shaft H⁶ is split at its forward end, as represented in Figs. 7 and 9, and is bored longitudinally for a part of its length, the bore receiving a core-discharger e. The inner end of the core-discharger has a connected pin that is extended through slots e' of the shaft H⁶, said pin entering a suitable collar c². 120

The fork G^X is provided with a screw-thread, by which to attach the fork to the split end 125 of the shaft H⁶, and the fork has a longitudinal central hole through which the core-discharger e may be moved.

At the proper time the core-discharger is moved forwardly with relation to the shaft H⁶ 130 and the fork G^X by means of an actuating device e³, shown as a curved lever, pivoted at

5 e^4 and having a backwardly-extended arm e^5 , that is acted upon at proper times after the fruit has been removed from the fork by the coring-blade to discharge the core from the fork, the actuator e^3 deriving its motion from a suitable projection at the foot of the carriage A^6 .

In the operation of the device let it be assumed that the knife-carrier occupies its farthest position to the left, Figs. 1 and 2, the position in which it is left after the action of the segmental rack D^7 on the gear D^8 , and that the coring-blade is thrown up and is in the position occupied by it when the pared fruit was discharged therefrom. In this condition the fruit to be pared—such, for instance, as an apple—is placed upon the fork G^x in usual manner, and the fruit acting against the carrier or its blade pushes the carrier away from the longitudinal center of the shaft H^6 against the stress of the spring b^3 . Now turn the gear H^4 and start the gear D^5 in the direction of the arrow thereon, Fig. 1, and immediately the first tooth of the partial gear D^4 will engage the teeth of the pinion D^3 and will turn the shaft D^2 in a direction to move the carriage A^6 to the right. During this movement the coring-blade will come into its horizontal position and will enter the fruit and the turn-table will be started and revolved in the direction of the arrow, Fig. 5, causing the paring-blade held by the spring b^3 and contacting with the inner end of the apple to travel about the apple from its inner 35 toward its outer end, thus paring the apple, and at the same time the coring-blade passes through the apple and cuts out the core, leaving it held by the fork. During this movement of the coring-blade it is prevented from 40 moving laterally or vertically or other than longitudinally forward by reason of its firm hold between the bushing and the split hub and by reason of the projections b^x running squarely on the guide C . The turn-table is 45 turned a half-revolution about the post E^2 . As the paring-knife finishes the paring the coring-blade completes the cutting of the core, and at this time the carriage A^6 reaches its extreme throw to the right and the last tooth to 50 the left of the partial gear D^4 retires from contact with the pinion D^3 , letting the first tooth of the rack D^7 engage the said pinion and rotate the shaft D^2 in the opposite direction, returning the carriage at a relatively greater 55 speed than the speed at which it was rotated during the paring and coring operation. As the carriage retires to its starting position the coring-blade withdraws the cored apple from the fork, and as the lug b strikes the adjustable 60 stud C^5 the coring-blade is tilted, causing the apple held by the paring-blade to meet the doffer C^6 , thus discharging the apple from the paring-blade. As the carriage A^6 nears the 65 end of its stroke to the left a pin, cam, or lug upon the outer part of gear D^5 strikes a projection attached to the arm E^5 of the actuator e^3 and moves said actuator, so that its up-

per split end embracing the shaft H^6 acts against the collar e^2 and slides the core-discharging device to the left, effecting the discharge of the core from the fork, leaving the parts at the completion of a cycle of operation in position to have another apple placed on the fork and the operation repeated. 70

Having described my invention, what I 75 claim, and desire to secure by Letters Patent, is—

1. In a fruit-parer, a carriage having a turn-table provided with a knife-carrier and knife for paring fruit, a rack connected with said carriage, a wheel having a partial gear, and a segmental rack, a shaft having two toothed gears one always in engagement with said rack, and the other actuated by said partial gear to move said carriage and by said toothed 85 segment to move said carriage in the opposite direction.

2. In a fruit-parer, a carriage having a turn-table provided with a knife-carrier and knife for paring fruit, a rack connected with said carriage, a shaft having a gear, a partial gear having teeth extended outwardly from said shaft, and a toothed segment connected with said gear, the teeth of the segment extending toward said shaft, a shaft having a gear engaging said rack, and a second gear to be engaged intermittently by said partial gear and by said segment, that the shaft having the gears engaging said rack may be rotated first in one and then in the opposite direction to 100 move the carriage in one and then in the opposite direction.

3. In a fruit-parer, a fork to hold the fruit, means to rotate the fork, a carriage having a rack, a slotted turn-table mounted thereon, 105 a rod sustained by said turn-table and movable in the slot thereof, a knife-carrier and knife, a shaft having a plurality of gears one of which is in constant engagement with the rack of said carriage, and means to engage 110 and rotate said shaft in one and then in an opposite direction at different speeds, the faster the speed of the shaft and carriage being after the paring has been completed and while the carriage is being returned into its 115 starting position.

4. In a fruit-paring machine, an overhanging frame, a carriage, means to move said carriage in said frame, a post depending from said carriage, a fork to hold the fruit, 120 a turn-table having a sleeve-hub provided with a projection and surrounding said post loosely, the longitudinal axis of said turn-table intersecting the longitudinal axis of said fork, a lever suspended at its upper end 125 on said projection, and provided with a paring-knife carrier, and a coring-blade depending from said frame, said paring-knife and coring-blade performing their respective work under the overhanging part of the frame. 130

5. In a fruit-parer, a carrying-sleeve, a bushing seated within said sleeve the exterior of which bushing in contact with said carrying-sleeve is shaped externally to conform

with the circle occupied by the convexed outer side of the coring-blade, said bushing having a portion cut away in the length thereof to conform with the circle of the interior of said coring-blade.

6. In a fruit-parer, a corer, and means to sustain the same, comprising a split carrying-sleeve and a bushing, the exterior of the bushing throughout its length occupying a position in different circles, the larger circle corresponding with the circular exterior of the coring-blade, and the smaller circle corresponding with the circle of the interior of the blade.

7. In a fruit-parer, a reciprocating carriage, an arch-plate connected therewith having a depending post provided with a shoulder, a rod having an attached knife-carrier, a turn-table having teeth at its lower end and provided with two projections, the upper projection sustaining one end of said rod, the lower projection being slotted to embrace said rod, a toothed plate to engage the teeth

of the turn-table and turn the same about said post as the carriage is moved to and fro and yielding means for holding the rod in the slotted projection.

8. In an apple-paring machine, a fork-shaft and fork, a carriage, a turn-table sustained thereby, a rod sustained by said turn-table, a knife-carrier connected with said rod and provided with a knife, and a plate connected with said carriage, and having a series of notches either one of which may be entered by said rod between its ends after the paring of each apple to thereby prevent the knife attached to the knife-carrier from striking the fork of the fork-shaft.

In testimony whereof I have signed my name to this specification in the presence of two subscribing witnesses.

LUCIEN I. YEOMANS.
